UNITED STATES PATENT OFFICE

FRANK C. DELI AND WILLIAM D. GROSECLOSE, OF CHICAGO, ILLINOIS, ASSIGNORS TO
AUTOPPOINT COMPANY, OF CHICAGO, ILLINOIS, A CORPORATION OF ILLINOIS

PENCIL

Application filed August 25, 1930. Serial No. 477,624.

Our invention relates to pencils and more particularly to mechanical pencils.

It is conceded that there are innumerable methods and manners of constructing the common mechanical pencil, some of which are quite inefficient and the others serving to produce an inferior, troublesome construction. A further objection to the common form of mechanical pencil relates to the tip thereof, which is generally formed of metal and contacts the lower end of the pencil barrel. In use it has been found undesirable to provide the entire tip of metal for the reason that the tip is thereby rendered quite slippery and frequently causes perspiration to form on the fingers if the pencil is used for any great length of time, thus making the use thereof somewhat unsatisfactory.

An object of our invention is to provide a molded tip, the greater portion of which is non-metallic, to secure the advantages and avoid the objections above set forth.

A further object of our invention is to provide a tip construction of the utmost simplicity and economy of manufacture, there being only two parts comprising the tip, the greater portion being non-metallic and molded over the lead tube.

Our invention will be more readily understood by reference to the accompanying drawing, in which:

Fig. 1 is a longitudinal sectional view through a pencil constructed according to our invention;

Fig. 2 is a cross sectional view taken on the lines 2-2 of Fig. 1;

Fig. 3 is a cross-sectional view taken on the lines 3-3 of Fig. 1, and

Fig. 4 is a fragmentary longitudinal sectional view of a modified form of tip construction.

By reference to Fig. 1 it will be seen that we have provided a barrel 10 having an axial opening 11 therein, an eraser 12, and at the lower end thereof the reduced portion 13 having the shoulder 14. The tip comprises the lead tube or guide 15 the lower end of which is split at 16 to insure the retention of a lead. Near the lower end of the tube 15 we provide a circumferential groove for a

purpose to be later described. The upper end of said tube 15 is adapted to be received within the aperture 11 of the barrel 10, and is provided with an internal thread 18 for co-operation with the threads 19 on the 55 plunger 20 adapted to travel therethrough and to force a lead (not shown) out from the lower split end 16. At the lower end of the tube 15, we provide the tapered non-metallic molded portion 21, the lower end of which 60 is adapted to be received within the groove thus providing an anchor therefor. The upper portion of said molded portion 21 is provided with a socket 22 adapted to co-operate with the reduced end portion 13 of the barrel. The upper peripheral edge 23 of the 65 molded portion 21 is adapted to contact the shoulder 14 on the barrel.

Thus it will be seen that we have provided a tip of two parts molded together. The 70 provision of the groove 17 serves a double purpose; first, to serve as a limit for the molded portion, and second, to anchor the same firmly to the tube. Obviously the lack of the groove 17 would subject the otherwise 75 very thin lower end of the molded portion to possible chipping or breaking off.

We have shown another form of our tip in Fig. 4 wherein the parts are substantially identical except for the tip which comprises the metal tip portion 24, the lead tube 25 centrally disposed therein, and the molded portion 26 serving to unit the tip and the lead tube. As shown the tip 24 is provided at its upper end with a crimped edge 27 serving 80 as an anchor when the molded material is forced past it. The upper end of the molded portion 26 is suitably formed to interfit with the lower end of the pencil barrel and to contact the shoulder thereon. If desired the 85 lower end of the tip portion 24 may have the slit 28 to provide for expansion when the lead is forced therethrough.

Obviously our construction is of the utmost simplicity and economy of manufacture 90 and provides a tip which is all that is desired in a writing implement, as well as the advantage of the availability of various colors in the molded material if desired.

Obviously modifications and variations 100

may be made in the two forms disclosed, and we do not wish to be limited except as indicated in the appended claim.

We claim:

- 5 In combination, a cylindrical pencil body composed of non-metallic moldable material having an axial opening, the lower end of the body providing a reduced portion and a shoulder, a tapered portion also composed
10 of non-metallic moldable material and having a socket adapted to receive the reduced end of the body, the upper end of the tapered portion lying against said shoulder, whereby the line of separation is at the junction of
15 the cylindrical body with the tapered portion, a metal tube firmly anchored within said non-metallic moldable tapered portion and adapted to project into the axial opening in the body, and lead advancing mechanism cooperating with said tube and body.
- 20

In testimony whereof we have affixed our signatures.

FRANK C. DELI.

WILLIAM D. GROSECLOSE.
